John J. Schlumberger,
By Samuel N. Tandy, Atty.

UNITED STATES PATENT OFFICE.

JOHN J. SCHLUMBRECHT, OF CHICAGO, ILLINOIS.

PIANO GUARD.

Application filed February 27, 1922. Serial No. 539,341.

To all whom it may concern:

Be it known that I, JOHN J. SCHLUMBRECHT, a citizen of the United States, residing at Chicago, in the county of Cook 5 and State of Illinois, have invented certain new and useful Improvements in Piano Guards, of which the following is a specification.

This invention relates to guards or shields 10 of the type designed to protect the front portion of a piano case immediately above and to either side of the pedals from injury and defacement through accidental contact with the shoes of children and other caretakers 15 less players who frequently scratch and otherwise mar the polished surface of the case through an improper application of the soles of the shoes to the pedals.

Various piano guards of this character 20 have heretofore been proposed, some of which are suspended from the under side of the keybed. Others are supported on the floor through feet which extend beneath the base of the piano case and are frictionally 25 held between the latter and the floor.

My present invention belongs to the latter type, and its main object is to provide a guard which will be readily adjustable to all sizes and makes of pianos. Another 30 object is to provide a device of this character wherein the guard plate holders shall be capable of adjustment to receive guard plates of varying thicknesses. A further object is to provide a device wherein the 35 holders or clamps which support the guard plate can be set at varying distances from the front of the piano case according to the structure of the pedals or the conformation of the lower front corner of the case. A 40 further object is to provide a shield or guard, the supporting feet of which shall be adjustable in height so as to engage with the floor and the base of the piano case regardless of the height of the latter from 45 the floor. A still further object is to provide a guard of this character that shall be adaptable to pianos having either a square lower front corner or a beveled lower front corner and shall co-operate with either 50 without danger of scratching or marring the finished surface of the case. Another object had in view is to provide a piano guard of neat, artistic and unobtrusive appearance which shall be an ornamental adjunct as well as a protector for a vulnerable 55 portion of the case.

Other objects and attendant advantages of the invention will become apparent to persons skilled in the art as the invention becomes better understood by reference to 60 the following detailed description, taken in connection with the accompanying drawing wherein I have illustrated one practical and approved embodiment of the invention, and in which—

Fig. 1 is a front elevation of the lower front portion of a piano showing my improved guard or shield applied thereto;

Fig. 2 is an enlarged transverse section taken on the line 2—2 of Fig. 1, showing 70 the device applied to a piano case having a rectangular lower front corner;

Fig. 3 is a view similar to Fig. 2, illustrating the application of the device to a piano case having a beveled or chamfered 75 lower front corner;

Fig. 4 is a horizontal section taken on the line 4—4 of Fig. 2, looking downwardly; and

Fig. 5 is a detail plan view of the bearing strip supporting spring.

Generally described, the device of my invention comprises a pair of duplicate substantially L-shaped guard plate holders, each of which consists of a vertically disposed clamp and a foot portion extending beneath the piano case and frictionally held between the bottom of the latter and the floor, and a guard plate, which is preferably of glass or other transparent material, 90 straddling the pedals and removably supported and held by the vertical clamps of the holders.

Since the holders are duplicates, a description of one will suffice for both. A 95 flat metal strip is bent to rectangular form, providing a flat vertical portion 10, and a flat horizontal foot portion 11. A similar but thinner metal strip is likewise bent to substantially rectangular form, providing 100 an upstanding and slightly bowed spring finger 12, and a base or foot portion 13. The base portions 11 and 13 of these strips are superposed, as shown in Fig. 2, one of them, such as 11, being provided with a 105 longitudinal slot 14 and the other being countersunk to receive the head of a clamp bolt 15, whereby the base members 11 and 13 are united with capacity for longitudinal adjustment by virtue of which adjustment 110 the spring finger 12 may be disposed at varying distances from the vertical mem-

ber 10 to accommodate guard plates of different thicknesses.

Adjustably mounted on the base member 11 is a strip 16, one end of which is bent or offset, as shown at 17 to form an adjustable fulcrum for a flat spring 18, the lower end of which latter is engaged beneath an anchor hook 19 secured to the rear end of the base 11 as by a rivet 20, 10 while the inner or front end of the spring 18 is formed with an upstanding pin or stud 21 (Fig. 5). Supported on the free end of the spring 18 is a flat bearing strip 22 which, as best shown in Fig. 3, is formed with a longitudinal series of holes 23, anyone of which may be engaged with the pin 21 of the spring, whereby the bearing strip 22 is adjustable lengthwise, and whereby 15 also said bearing strip, being pivoted on the spring, may automatically adjust itself to the surface of the under side of the baseboard B of the piano case. The forward end of the strip 22 is bent upwardly, as shown at 22' in Figs. 2 and 3, and is 20 covered by a sleeve or hood 24 of rubber, felt or soft material adapted to have a bearing against the lower front wall of the base of the case and serve as a stop to determine the spacing of the guard plate 25 clamps from the front surface of the piano case.

25 designates the guard plate which is preferably made of plate glass, and is cut out on its under side to straddle the pedals indicated at P, the lower side portions of the plate 25 fitting into the spring sockets or clamps formed by the members 10 and 12 of the holders. When so fitted, the guard plate 25 is securely supported in place, but 30 may readily be removed by a simple lifting movement.

From the foregoing it will be seen that the device of my invention is readily adjustable and hence adaptable to various 45 heights of piano case bases and to various contours and finishes of the portions of the case adjacent to the pedals. For instance, in Fig. 3 I have illustrated the application of the device to a piano case the lower front 50 corner of which is beveled or chamfered as shown at B', this permitting the guard plate 25' to be set somewhat closer to the front of the case than in the structure of case shown in Figs. 1 and 2. Where the 55 baseboard of the case is higher from the floor than that indicated in Fig. 2, the bolt 15 is loosened and the fulcrum strip 16 is adjusted to shift the fulcrum 17 closer to the anchor 19, which correspondingly elevates the free end of the spring 18 and the bearing strip 22 supported thereby. In the 60 case of a lower baseboard the fulcrum 17 is adjusted in the other direction. The described structure enables the feet of the 65 holders to be adjusted through a very con-

siderable vertical range; while the longitudinal adjustability of the bearing strip 22 on the spring 18 enables the vertical clamps 10, 12, to be set at any desired or necessary distance from the front of the 70 piano case.

By making the guard plate 25 of glass, the finish of the piano case lying behind the same is, of course, not concealed or occluded, so that the guard plate itself is 75 hardly visible except upon close inspection. Where, however, a cheaper construction is desired, the glass guard plate may be replaced by one of wood, metal, or any other material, its particular thickness being of 80 no consequence since the clamp fingers 12 are adjustable to hold it regardless of its thickness.

The use of clamps to hold the guard-plate has a further advantage in that it enables the guard-plate to be set higher or lower, according to the height of the piano 85 pedads above the floor.

While I have described one practical embodiment of my invention which in practice 90 has been found to fulfill the stated purposes and objects thereof, it will be manifest that the structure shown and described may be variously modified in respect of details without altering the substantial character and principle of the invention or sacrificing any of the advantages thereof. Hence I reserve all such variations and modifications as fall within the spirit and 95 purview of the appended claims.

I claim—

1. In a piano guard of the character described, the combination of a pair of vertical clamps disposed on opposite sides of the piano pedads respectively, each of said clamps having a foot extending beneath the base of the piano case, and a guard plate straddling the pedads and supported by said clamps.

2. In a piano guard of the character described, the combination of a pair of transversely elastic vertical clamps disposed on opposite sides of the piano pedads respectively, each of said clamps having a horizontal transversely elastic foot bearing against 115 the base of the piano case, and a guard plate straddling the pedads and removably held by said clamps.

3. In a piano guard of the character described, the combination of a pair of widthwise adjustable vertical spring clamps disposed on opposite sides of the piano pedads respectively, each of said clamps having a horizontal foot lying between the base of the piano case and the floor, and a guard plate 125 straddling the pedads and supported by said clamps.

4. In a piano guard of the character described, the combination of a pair of guard plate holders each comprising an upright 130

strip, an upright spring finger substantially parallel with and spaced from said strip, and a horizontal foot extending beneath the piano case, and a guard plate straddling the 5 pedals and clamped between said upright strips and fingers.

5. In a piano guard of the character described, the combination of a pair of guard plate holders each comprising an upright 10 strip, an upright spring finger in front of and substantially parallel with said strip and adjustable toward and from the latter, and a horizontal foot extending beneath the piano case, and a guard plate straddling the 15 pedals and clamped between said upright strips and fingers.

6. In a piano guard of the character described, the combination of a pair of guard plate supports, each comprising an upright 20 socket member and a horizontal foot member extending beneath the bottom of the piano case, a spring mounted on said foot member, a bearing strip supported by said spring and pressed by the latter against the 25 bottom of said case, and a guard plate removably mounted in said socket members.

7. In a piano guard of the character described, the combination of a pair of guard plate supports, each comprising an upright 30 socket member and a horizontal foot member extending beneath the bottom of the piano case, a spring mounted on said foot member, a bearing strip supported by said spring and pressed by the latter against the 35 bottom of said case, an upwardly extended stop on the end of said bearing strip, and a guard plate removably mounted in said socket members.

8. In a piano guard of the character described, the combination of a pair of guard plate supports each comprising an upright 40

socket member and a horizontal foot member extending beneath the bottom of the piano case, a spring mounted on said foot member and provided with a pivot lug on its upper 45 end, a bearing strip formed with a longitudinal series of seats for said pivot lug and pressed by said spring against the bottom of said case, an upwardly extended stop on the end of said bearing strip, and a guard 50 plate removably mounted in said socket members.

9. In a piano guard of the character described, the combination of a pair of guard plate supports each comprising an upright 55 socket member and a horizontal foot member extending beneath the bottom of the piano case, a flat spring anchored at its lower end on said foot member, a fulcrum for said spring mounted on and adjustable 60 lengthwise of said foot member, a bearing strip mounted on the upper end of said spring and pressed by the latter against the bottom of said case, and a guard plate removably mounted in said socket members. 65

10. In a piano guard of the character described, the combination of a pair of guard plate holders each comprising inner and outer L-shaped members having their horizontal limbs superposed and united with 70 capacity of relative longitudinal adjustment whereby their vertical limbs may be spaced to receive guard plates of varying thicknesses, a spring mounted on the horizontal limb of said inner member; a bearing strip pressed by said spring against the base of the piano case, and a guard plate straddling the pedals and held between the 75 spaced vertical limbs of said L-shaped members.

JOHN J. SCHLUMBRECHT.
